CUTTING AND CREEASING PRESS

Lloyd A. Whittaker and Harold F. Peterson,
Franklin, Mass., assignors to Thomson-Na-
tional Press Co., Inc., Franklin, Mass., a cor-
poration of Massachusetts

Application March 8, 1944, Serial No. 525,618

11 Claims. (Cl. 164—19)

1

The present invention relates to improvements in cutting and creasing presses for the purpose of cutting and creasing such flat materials as paper, impregnated papers, cardboards, corrugated cardboard, composition materials, plastics, fabrics, wood and plywood, rubber and even soft metal materials.

Cutting and creasing presses and likewise other types of presses are as a rule of two general forms; one, the rotary cylindrical press, and two, the flat bed press.

In the flat bed press the cutting and creasing die is set into the underneath side of a flat head and the sheet is placed on a flat table, the head and table being brought together over their whole surface, cutting or creasing the whole sheet which may have been placed on the table at the same time. Very large machines of this type have been built of such a size as to take a sheet 50" x 80" with the result that very great pressure is necessary between the head and the table to force the cutting and creasing dies into or through the materials, especially for such materials which are heavy and hard.

In the rotary press the material is fed over a large rotary cylinder and the die or creasing forms set into a flat bed which reciprocates back and forth, in one direction coming in contact with the sheet which is wrapped around the cylinder and pressing and creasing it, and in the other direction dropping from contact with the cylinder in preparation for cutting and creasing the next sheet. In the cylindrical cutting and creasing press the flat plate is always tangential to the cylinder in the cutting and creasing operation so that only one line of cutting dies, transverse of the platen, exerts pressure at a time on the sheet to be died out, the cylinder in effect rolling over the platen plate.

The present invention provides a number of advantages over the cylindrical press in addition to this feature of the cylindrical press, that only a tangential portion of the platen cutter meets the table so that the pressure is not that which would be necessary to cut and crease a whole sheet at once.

In the present invention the head holding the cutting and creasing dies is stationary and the table which is arcuate is both oscillated and reciprocated in the cutting and creasing operation. This permits the design of a simple motion which at all times is readily balanced in the machine and makes it unnecessary for the head to slide to a stop at the end of each oscillation. Further, the oscillation of the arcuate table permits the

2

material to be fed in readily at one end and to be taken out at the other end during the movement of the arcuate table back to its initial position.

A further advantage of the present invention is that essentially there is only one moving part as the table does both the reciprocation and the oscillation in the cutting and creasing operation.

Other and further advantages of the present invention will be more readily understood in connection with the specification annexed hereto describing the invention in connection with the drawings showing an embodiment of the same in which:

15 Figure 1 shows a side view of the cutting and creasing press with portions shown in dotted position.

Figure 2 shows another side view of the invention with portions shown in fragmentary sections and elements in a different position than shown in Figure 1.

Figure 3 shows a section through the machine with the center broken away taken on the line 3—3 of Figure 2.

25 Figure 4 shows a section substantially similar to Figure 3 through a portion of the machine.

Figure 5 shows an end view of the machine viewed from the right of Figures 1 and 2.

Figure 6 shows a detail of the top portion of the machine with the head in an extended position.

Figures 7, 8 and 9 show enlarged details.

In the figures, 1 is the frame which is provided with two large side plates 2 and 3 which may be of cast metal or other suitable material.

35 The plates 2 and 3 have top finished bearing surfaces 4 and 5 with recessed tracks or grooves 6 and 7 in which are positioned two groups of rollers 8 and 9 respectively, journalled in side bars, 10 and 11 for the rollers 8, and 12 and 13 for the rollers

40 9. These sets of rollers run freely on the frame and support the top head or die holder 14 which is provided with two extending flanges 15 and 16 resting or bearing on the rollers 8 and 9 respectively.

45 The head 14 is also provided with bearing surfaces 17 and 18 bearing against corresponding surfaces 19 and 20 on the arcuate table 21 which will be described in more detail later.

The head 14 has formed as an integral part

50 of it a flat plate 22 in which the cutting or creasing dies 23 are set. These are of the usual construction and are held in place by a chase 24

clamping the cutting and creasing dies in place.

The head 14 is ribbed and arched for support

55 and while it is adjustable on the side supports

of the frame, in its use and operation it is clamped in place. This is accomplished by means of angular, supporting and clamping brackets 25 and 26 which are bolted to the side portions of the frame 2 and 3 by means of a series of bolts 27 and 28 respectively. Wedging clamping bars 29 and 30 recessed slightly in the inwardly extending flanges of the brackets 25 and 26 serve to clamp the head rigidly in position after its position has once been adjusted. These wedges 29 and 30 may be simultaneously operated by means of the operating bar 31 (see Figure 5) which will be presently described.

The head 14 on one side is provided with a rack 32 which is fastened to the side edge of the flange 15. Meshing with the rack 32 is a pinion 33 which is journalled in a forked bearing 34 which is fastened to the side bracket 25. The pinion 33 is operated by means of the handle 34 which turns a crank arm 35 rotating the shaft 36 on which the pinion 33 is mounted. By turning the crank arm 34, therefore, the head may be extended from the position shown in Figure 2 to the position shown in Figure 6 or in any intermediate position. A plurality of end stops 37 and 38 are provided for limiting the motion of the head beyond the end of the frame.

The wedging previously briefly described is controlled by means of the operating bar 31. This bar at each side of the frame is provided with crank arms 39 and 40 to which the shafts 41 and 42 are attached. These shafts are journalled in the top portions 43 and 44 of the side brackets 25 and 26 and are provided at their ends with eccentrically positioned pins 45 and 46 operating in transverse slots 47 and 48 in the wedges 29 and 30. These wedges are tapered as seen in Figure 6.

The head 14 is moved to the left, as viewed in Figure 6, in order to permit working room for the operator to set in place the chase and cutting and creasing dies without being troubled by the arcuate table 21. When this has been accomplished and when the arcuate table has also been fully prepared or "made ready" as will be explained, the head is brought back to position, the position shown in Figure 1 or Figure 2 and is locked in its proper place. This is accomplished by forcing the wedge to the left, as viewed in Figure 6, by pulling on the bar 31. The wedges 29 and 30 are thereby forced in between the flanges 15 and 16 of the head and the flanges 43 and 44 of the brackets 25 and 26 thereby firmly tightening the head in its position. The head is, of course, swung in or out to the proper position by means of the crank 34 before the tightening of the wedge is accomplished.

The cutting and creasing dies may be set in the head in any well known manner. This is commonly done by setting the knife edges as, for instance, 49, Figure 3, in a wooden or other supporting piece and surrounding it by pieces of rubber or cork 50 and 51 which serve to aid in ejecting the work after it has been cut or creased by the knife. The material to be cut is fed onto the arcuate table 21. This may either be done by hand or the sheet may be fed automatically by a feeding mechanism of any of the well known types. The feeding may be done from one end and the piece may be taken off from the same end or from the opposite end. In Figure 5 the grippers 99 are shown at the end of the table. These may be mechanically operated by a rod and cam at a given position of the table in any

manner. The taking off may also be done manually or automatically by methods common in the art. The arcuate table 21 may be made of cast or other metal material and is freely supported by a shaft 52 about which it is free to turn. The arcuate table 21 may have a number of supporting brackets, as shown in Figures 3 and 5. The shaft 52 is itself journalled in carriages 53 and 54 which are slidable on rollers in slots in the side portions 2 and 3 of the main frame.

This construction is shown in Figures 1, 2 and 5 and 10. The carriages 53 and 54 which slide in slots 55 and 56 in the frames 2 and 3 furnish the bearings for the extensions 57 and 58 of the shaft 52 in such a manner that the shaft 52 is eccentrically positioned with respect to these extensions 57 and 58. In the position shown in Figure 3, the shaft 52 is in its highest position. The extension 57 at the left of Figure 3 is supported by a toggle joint support which lowers the shaft 52 when it is rotated eccentrically about its extensions 57 and 58. This is accomplished by means of the crank arm 59 in which the end of the shaft 57 extends. The bell crank arm 60 has pivoted to its free end a bell crank lever 61 which is pivoted at the fulcrum 62 and linked by means of the pivot 62 to the crank arm 63 which is journalled to the shaft 64 of one of the rollers 65 of one bearing in the sliding carriage for the shaft 52. In the position shown in Figure 10, the arm 66 of the bell crank lever 63 is extended vertically downward and will remain in this position until the arcuate table has been carried to one end of the frame, the left end as viewed in Figure 1. It will thereupon strike the stop 66' and be thrown to the right whereupon the crank 59 will be moved to the right, as viewed in Figure 10, and the shaft 52 will thereby be dropped. The crank 59 and the extension 57 are tied together by a key-way 66 or by any other suitable means. This dropping of the shaft 52 will provide clearance between the arcuate table and the cutting and creasing head.

As shown in Figures 1 and 2, the arcuate table 21 is provided with a sector gear 67 which engages a fixed rack 68 attached to the side frame 2. This is shown in Figures 3 and 4. The rack 68 is fixed to the frame in a permanent position and not to the head 14 since the head must be adjusted for removal of the dies and for access to the arcuate table. The arcuate table 21, as has been explained above, has both an oscillating and reciprocating motion. For this purpose there is provided a harmonic drive shown in dotted position in Figures 1 and 2. This includes a drive shaft 69 which may be driven by a motor through a reduction gear with the initial driving arm or crank 70 linking with a second crank 71 which is attached to the shaft 52 in the collar or bearing 72. The drive for the shaft is preferably at a number of points through several cranks and bearings 72 and 73. By means of this drive, the shaft 52 and its supporting carriages 53 and 54 which are mounted on the rollers 65 and 65' are moved from one end of the slots 55 to the other end of the slot with a harmonic motion with zero velocity at each end of the slot. At the right end of the slot the toggle detent 66 hits against the stop 66' and drops the shaft 52. Any other suitable means may be used to throw out and in the toggle detent at the end of the motion. As has been explained, the continued motion of the drive crank pulls the arcuate table back to its initial position where the arm 66 of the bell crank lever comes in contact with the other stop 74 which

raises the shaft 52 back in position where the arcuate table comes in contact with the head, the bearing flanges 17, 18, 19 and 20 serving as a guide for the engagement of the table and the head. In the motion of the arcuate table, the sector gear 67 meshes with the rack 68 so that the arcuate table oscillates or rotates on the shaft 52 at the same time that its axis is reciprocated back and forth beneath the head.

In the arrangement shown in the present application, cutting and creasing takes place as the arcuate table (as viewed in Figures 1 and 2) has its axis moved from the right to the left. In the reverse motion the table is disengaged from the head to a degree such that no cutting or creasing takes place.

It should be noted, however, that in this operation the sector gears 67 and the rack 68 are large and will continue to mesh even though the table has been dropped a considerable amount. This insures that the cutting and creasing operation will be accurately repeated for each stroke.

One of the advantages of the present arrangement is that the arcuate table may be made clear of the head by moving the head out from above it. This permits the arcuate table to be "made ready" with considerable ease as the operator has easy access to the arcuate table.

The table is properly built up in the well known manner to the proper height by layers of paper or other materials after which the cover 80 is drawn tautly over it and clamped in position by the clamp 81. (See Figure 2.)

The press herein described may be made in any desirable size but has a prime advantage in that it may be made in very large sizes and operated at a rapid rate, more rapidly than has been accomplished with machines of the prior art of the flat bed type.

It will readily be appreciated that modifications and changes may be made in the present construction for automatic and manual operation without radically departing from the spirit or scope of the present invention and we therefore claim as our invention:

1. In a cutting and creasing machine, a frame, a head mounted thereon, an arcuate sector table positioned and adapted to be in substantially tangential contact with said head and having a supporting shaft upon which said sector table is freely rotatable and means providing a harmonic motion with substantially no velocity at the end of the motion for reciprocating the shaft through a given stroke.

2. In a cutting and creasing machine, a frame, a head slidably positioned on said frame, an arcuate sector table positioned and adapted to be in substantially tangential contact with said head and having a supporting shaft upon which said sector table is freely rotatable, means for reciprocating the shaft longitudinally of the head and frame, means inter-connecting the table and frame for oscillating the table during the reciprocating motion, and means for sliding said head from a position over said table to a position clear thereof.

3. In a cutting and creasing machine, a frame, a head mounted thereon, an arcuate sector table positioned and adapted to be in substantially tangential contact with said head and having a supporting shaft upon which said sector table is freely rotatable, means for reciprocating the shaft without rotation longitudinally of the head and frame, and means interconnecting the table and frame for oscillating the table during the recipro-

cating motion, said last-named means comprising a rack mounted in said frame and a sector gear mounted on said table and engaging therewith.

4. In a cutting and creasing machine, a frame, a head mounted thereon, an arcuate sector table, a shaft on which said table is pivoted, a carriage movably supported with respect to said frame for carrying said shaft, said carriage eccentrically supporting said shaft means for reciprocating the shaft longitudinally of the head and frame, means inter-connecting the table and frame for oscillating the table during the reciprocating motion, and means included in part in said carriage for rotating said eccentrically mounted shaft at the ends of the motion thereof to engage and disengage said table from said head.

5. In a cutting and creasing machine, a frame having a bearing flange, a head having a bearing flange slidably mounted on said frame, an elongated wedge, means for tightening said wedge between the frame and said head in the bearing flanges, an arcuate sector table having a shaft upon which said sector table is freely journaled for supporting the same, means for reciprocating the shaft longitudinally of the head and means inter-connecting the table and frame for oscillating the table during the reciprocating motion.

6. In a cutting and creasing machine, a frame, a head positioned thereon, means for sliding said head with respect to said frame comprising a pinion mounted on one of said elements and a rack on the other thereof, an arcuate sector table positioned and adapted to be in substantially tangential contact with said head and having a supporting shaft upon which said sector table is freely rotatable, means for reciprocating the shaft longitudinally of the head and frame, means inter-connecting the table and frame for oscillating the table during the reciprocating motion, and means co-operating with the head and the frame for locking said head in position for normal operation.

7. In a cutting and creasing machine, a frame having guide channels in the sides thereof, a flat head, sliding bearing means supporting the head in the guide channels, means for adjusting and fixing said head in a selected position along said sliding bearing, an arcuate sector table positioned and adapted to be in substantially tangential contact with said head and having a supporting shaft upon which said sector table is freely rotatable, a sector gear carried concentrically by said sector table, a rack fixedly positioned longitudinally with respect to said head and adapted to mesh with said sector gear, and means for reciprocating said shaft in a direction parallel to the motion of the head in said guide channels.

8. In a cutting and creasing machine, a frame, a head mounted thereon, an arcuate sector table positioned and adapted to be in substantially tangential contact with said head and having a supporting shaft upon which said sector table is freely rotatable, means for reciprocating the shaft longitudinally of the head and frame comprising a pair of roller carriages mounted in elongated slots and supporting said shaft at its ends for free motion longitudinally of said slots and a crank arm drive for reciprocating said carriage in said slot.

9. In a cutting and creasing machine, a frame, a head mounted thereon, an arcuate sector table positioned and adapted to be in substantially tangential contact with said head and having a supporting shaft upon which said sector table is freely rotatable, means for reciprocating the shaft

longitudinally of the head and frame comprising a pair of roller carriages mounted in elongated slots, means supporting said shaft at its ends in said carriages comprising toggle joint means having an eccentric element formed as an extension of said shaft whereby when said toggle is operated the shaft will be lowered, lowering the sector table from said head and a crank arm drive for reciprocating said carriage in said slot and means operative at the end of the stroke for raising or lowering the shaft.

10. In a cutting and creasing machine, a frame, a head having a flat surface mounted thereon, an arcuate sector table in substantially tangential contact with said head, a shaft supporting said table, a carriage journalling said shaft and permitting free rotation of the same and said table, said machine having a single drive source comprising means providing translatory motion for

said carriage parallel to the surface of said head, and means inter-connecting said head and said table for oscillating the table during translatory motion of the carriage.

11. In a cutting and creasing machine, a frame, a head having a flat surface mounted thereon, means for fixing the head in a desired position for operation, an arcuate sector table in substantially tangential contact with said head, a shaft supporting said table, a carriage journalling said shaft and permitting free rotation of the same and said table, said machine having a single drive source comprising means providing translatory motion for said carriage parallel to the surface of said head, and means interconnecting said head and said table for oscillating the table during translatory motion of the carriage.

LLOYD A. WHITTAKER.
